FRIEDRICH WILHELM BAUMGÄRTNER, OF BERLIN-SCHONEBERG, GERMANY, AS-
SIGNOR TO F. A. BAUMGARTNER, DR. KATZ & CO. G. M. B. H., OF EISWERBER-SPAN-
DAU, GERMANY.

MANUFACTURE OF HOLLOW BODIES FROM FIBROUS MATERIAL PULP.

Application filed April 21, 1923, Serial No. 633,660, and in Germany November 16, 1922.

The invention relates to a method of manufacture of hollow bodies, for example, packing material and useful articles of fibrous material pulp such as wood pulp, cellulose 5 or textile fibers.

Processes are known, for example, using paper pulp, in which with the aid of a heated gaseous pressure medium such as compressed air, steam and the like, hollow 10 bodies are produced in moulds with permeable walls. By none of these methods was 15 it possible to manufacture hollow bodies of any desired volume limited only by the size of the mould with smooth cardboard interior surfaces in an efficient manner. The condition of the inner surface, however, is, of particular importance for the general use, for example, in the packing of foods or for 20 technical requirements.

The preliminary requirements for the production of smooth interior surfaces are as follows:

The moulding must be effected so far as 25 possible by hydrostatic pressure before the heated gaseous pressure medium drives the pulp against the permeable walls of the mould, presses out the superfluous water and comes into contact with the walls of the mould. It will be understood also that the 30 process of moulding becomes all the more efficient the less compressed air or steam is required.

During its moulding and drying action on 35 the fibrous pulp, gyrations and pulsations of the gaseous pressure medium should be prevented because they result in roughening the interior surface. This is attained on the one hand by the above mentioned limitation of the action of the gaseous pressure medium 40 on account of the high percentage of hydrostatic moulding. So far as the gaseous pressure medium is still required, it is introduced in as uniform a manner as possible in a working direction which might be considered 45 as running parallel to the walls of the mould.

In order to mould hollow bodies in accordance with these preliminary conditions, the procedure is as follows: A preliminary 50 container is interposed in front of the mould to take the fibrous pulp, the concentration of which should be as small as possible. The preliminary container is connected with the mould by an inlet pipe which is to be dimen-

sioned so that the gaseous pressure medium 55 without producing gyrations traverses the mould. If for instance a hollow body of 25 grams weight is to be moulded, the concentration of the pulp amounting to 1:100, the preliminary container must be dimensioned 60 of at least 2,500 cubic centimetres capacity. The hollow body to be moulded should have 500 cubic centimetres capacity and also accordingly the mould.

Of the 2,500 cubic centimetres of the preliminary container, since the mould itself has only 500 cubic centimetres, 2,000 cubic centimetres are hydrostatically pressed through the mould. The percentage of hydrostatic moulding amounts however to 65 about 80. If, however, and in order to obtain smooth interior surfaces this is to be aimed at, the percentage of hydrostatic moulding is about 92 instead of 80, of the 70 500 cubic centimetres still 300 cubic centimetres should be displaced hydrostatically. In order to accomplish this without increasing the preliminary container which perhaps 75 in practice cannot be done or at least would be burdensome, a further device is used. The inner space of the mould is diminished by a built-in centred body according to this numerical example of 300 cubic centimetres capacity which should not touch the bottom of the mould. Furthermore, according to the 80 process on which the invention is based, the favorable condition of hydrostatic moulding without increasing the preliminary container can also be accomplished by the action of a 85 piston pressing in the mould. 90

Assuming the above, the moulding according to the invention takes place as follows:

The fibrous pulp is introduced into the preliminary container, usually automatically, and flows from the preliminary container into the mould. Then the heated gaseous pressure medium is introduced in such a way that it acts from above against the upper surface of the fibrous pulp introduced 95 for moulding in the described manner. The pulp flows almost parallel to the walls of the mould therein so that gyrations at the point of entry or elsewhere are avoided and almost the whole of the fibrous material contained 100 in the suspension is pressed against the walls of the mould by hydrostatic moulding; any fibres still remaining in the suspension 105

are then distributed by air on the interior walls. After the moulding and drying the mould opens out and the hollow body provided now with smooth interior surfaces is 5 ready for use without requiring any subsequent drying.

In the drawing two constructional examples of the mould are shown diagrammatically in cross section and elevation. The 10 fibrous pulp enters through the inlet pipe *a* into the preliminary container *b* and from this into the actual mould *c*. The introduction of the gaseous pressure medium is effected through *e*.

15 The moulds are, as is well known, permeable to air. In Figure 2, retaining all parts of Figure 1, there is further centred in the interior of the mould a body *f*.

Having now particularly described and 20 ascertained the nature of my said invention, and in what manner the same is to be performed, I declare that what I claim is:

1. Apparatus for molding hollow pulp bodies having smooth interior surfaces comprising a lower, permeable mold, an upper container, a body disposed in the mold to diminish the space within the mold, and 25

means for introducing gas under pressure into the container.

2. Apparatus for molding hollow pulp 30 bodies having smooth interior surfaces comprising a permeable mold and a container connected together, a body disposed in the mold to diminish the space within the mold, and means for forcing a fluid, under pressure, upon the surface of pulp liquor in the container and the mold and between the body and the walls of the mold and along the said walls from one end of the mold to the other end of the mold to force the pulp 35 liquor hydrostatically through the container and into and against the walls of the mold and to cause the pulp liquor to travel along the walls of the mold from the said one end of the mold towards the said other end of 40 the mold, whereby the fibrous material of the pulp liquor is distributed along the walls of the mold and there dried by the heated gas.

In testimony whereof, I have hereunto 45 subscribed my name this 16th day of March, 1923.

FRIEDRICH WILHELM BAUMGÄRTNER.
